UNITED STATES PATENT OFFICE.

HELEN C. GAMBLE, OF NEW YORK, N. Y.

BAG.

Application filed December 15, 1928. Serial No. 607,050.

This invention relates to bags.

An important object of this invention is to provide a portable container for such articles as hats, preferably in the shape of a drum, as such containers have been formed heretofore, of patent leather or material having the semi-rigid, but substantially self-collapse characteristics of patent leather, a primary feature of my invention being the provision of stiffening means, to support the container in expanded self-sustaining position and means to removably secure said stiffening means, in position so that when it is desired to collapse the container for packing, as in a trunk or dress-suit case when travelling, the holding means can be readily moved into position to permit such collapse.

Heretofore such patent leather hat containers have been constructed in permanently expanded shape, and so far as I am aware, I am the first to provide means for readily collapsing and expanding drum-shaped containers of this kind, thereby making possible their more convenient utilization as an article for travellers' use, by diminishing their bulk when not required to contain hats or other articles.

A further feature of the invention is to provide a bag with closure means and a handle or like supporting member for positively closing the closure means when the bag is carried by the handle.

A further feature of the invention is to provide a bag formed of leather or fabric or like non-self-sustaining material and stiffening members arranged relatively to the non-self-sustaining material to render the material self-sustaining.

Pursuant to the invention, the bag comprises material such as leather, fabric or the like, usually of circular contour, the material of one circular side and the body strip being sewed at their contiguous edges or otherwise permanently attached to one another, the material of the opposite circular side being partially sewed or otherwise permanently attached to the body strip and the remainder serving as a flap or otherwise unattached snap fasteners or other readily detachable connecting means for connecting the flap to effect closure of the bag; a set of coacting stiffening elements removably secured in stiffening position as by means of snap fasteners or the like and when detached are removed from stiffening position to afford col-

lapsibility of the material of the bag; a handle comprising a plurality of elements usually in the form of a pair of straps connected at their free ends by snap fasteners or the like, the opposite ends of the straps being respectively permanently secured to the body of the bag and to the flap whereby upon snapping the handle straps to one another the flap of the bag is secured against dropping and precludes the loss of any article enclosed within the bag.

Further features and objects of the invention will be more fully understood from the following description and accompanying drawings, in which

Fig. 1 is a perspective view of a bag of circular contour embodying my invention;

Fig. 2 is a top plan view of the bag in horizontal position, showing the handle straps detached and the closure flap of the bag in opened position;

Fig. 3 is a central vertical sectional elevation of the bag in vertical position, on an enlarged scale, and showing the closure flap of the bag in open position;

Fig. 4 is a detail perspective view of a portion of the interior of the bag and showing one form of stiffening element; the dotted outline shows the stiffening element in stiffening position and the full outline shows the stiffening element swung out of stiffening position;

Fig. 5 is a perspective view of a modification of the bag shown in Fig. 1 of double capacity;

Fig. 6 is a perspective view of a further modification of the bag embodying the invention;

Fig. 7 is a perspective view of the drum-shaped modification shown in Figure 6, but on a reduced scale; and

Fig. 8 is a perspective view of a further modification of the invention of general rectangular outline.

Referring to Figs. 1 to 4, the bag is illustrated of circular contour and in such form comprises the side member 10 of circular outline and may be made of leather, fabric or like non-self-sustaining material. The peripheral portion 11 is bound by stitching or the like at its edge 12 to the circular edge of the side member 10.

The opposite edge 13 of the peripheral body portion 11 is secured for a portion of its circumference to the opposite side member 14.

as by stitching or the like. Usually, the side member 14 is sewed for its lower circumferential half whereby the upper half indicated at 15, see Figs. 2 and 3, serves as a flap and 5 may be provided with the flange strip 16. The snap buttons 17^a, 17^b, in number as desired, may be secured respectively to the flange strip 16 and on the inner face of the upper circumference half of the edge 13 of 10 the peripheral body portion 11, for removably securing the flap 16 in closed position.

The handle in the strap form as illustrated comprises a strap member 20 secured at its lower end 21 by stitching or the like to the 15 material of the bag as between the contiguous edges of the side member 10 and the under side of the peripheral body portion 11. The other strap member 22 is secured at its end 23 to the upper edge of the flap 15, as between 20 the contiguous portions of the upper edge of the flap 15 and the flange strip 16.

For the purpose of rendering the bag self-sustaining, I provide stiffening means which may be in the form of a plurality of stiffening 25 members, such as strips 24, of fibre or the like and for effectuating the fabric of the bag self-sustaining. Such strips 24 may be four in number and distributed respectively at the top, the bottom and at the opposite sides. 30 The strips 24 may be secured at their inner ends 25 by stitching or the like to the inner face of either of the circular side members 10 and removably held in stiffening position by means of snap fasteners 26^a, 26^b, respectively secured to the adjacent face of a strip 24 and to the inner face of the circular strip portion 11.

The strips 24 may be provided with pockets 28 for jewelry, wearing and toilet articles 40 and the like.

The embodiment of the invention illustrated in Figs. 1 to 4, is primarily suitable for enclosing a hat and for such purpose the contour of the bag may be circular or drum-shaped. However, it will be apparent that the invention is applicable for enclosing other articles and the contour of the bag may be shaped in correspondence to such other article or articles or to provide advantages in 50 space or arrangement of a number of enclosed articles, as may be desired.

The bag illustrated in Fig. 5 is designed of double or other increased capacity as compared with the bag shown in Figs. 1 to 4, inclusive, suitable for a hat of enlarged design or for enclosing wearing apparel or other articles as well as one or more hats. The one circular side member 30 is fully attached to the peripheral body member 31 about the 60 complete peripheral edges thereof, similarly as hereinabove set forth and the other circular side member 32 may be connected to the peripheral body member 31 for the lower circumference thereof, the upper circular half 65 serving as a flap 33 and snap buttons 34^a

and 34^b provided for closing the flap 33. The pair of coacting handle straps 35, 36 are connected to one another by the snap buttons 37^a, 37^b.

In this modification, the flaps 38 are in the 70 form of sheets of fibre enclosed in suitable silk or other fabric and sewed at one end 39 to the inner face of one side member 30 and held in sustaining position by snap buttons 40^a, 40^b. The flaps 38 are shown as four in number 75 although the number of the same may be increased as desired, and the flaps 38 may alternately be connected to any one of the circular side members 30, 32 or to the peripheral member 31, as desired, whereby the flaps 38 80 when disconnected may all lie flat on the inner face of the circular side member 30 or but certain of the flaps 38 lie on the inner face of the circular member 30 and the remaining flaps 38 when disconnected lie flat on the inner face of the opposite side member 32.

In the modification shown in Fig. 5, auxiliary pockets may be applied on the inner faces of either or both of the circular side members 30, 32, or on the inner face of the central 90 body member 31 for holding or enclosing such articles as may be desired.

In the modifications shown in Figs. 1 to 4, and in Fig. 5, the stiffening flaps 24, 38, respectively may be retained in stiffening position by the use of snap buttons or the like and when disconnected from the snap buttons be free from any other part of the bag, and in this instance a pocket such as formed within the lining on the inner face of the bag may be 100 provided for receiving the stiffening flaps when not in use.

In the modification shown in Figs. 6 and 7, also illustrated as drum-shaped, the opposite flap, circular members 42, 43 are connected at their peripheral edges respectively to the annular members 44, 45, one of which, as for example 44, has its lower portion secured by stitching or otherwise to the central member 46 and its upper portion unsecured 110 to provide a closure flap 47, similarly as hereinabove set forth, and at the edges of the flap 47 is secured a strip 48 on which are disposed spaced snap fasteners 49^a for attachment to the respective coacting snap fasteners 49^b secured at the edge of the central member 46 for ready connection and disconnection of the closure flap 47. The handle in this instance comprises a pair of straps 50, 51, similarly as hereinabove set forth, one strap 50 being secured at its fixed end 52 at one side of the bag and the other strap member 51 secured at its end 53 to the flap 47. The snaps for connecting the strap members 50 and 51 are indicated at 54^a, 54^b.

If desired, the circular side members 42, 43 may be formed of leather or the like, and the annular members 44, 45 of contrasting material such as plush or the like and may be 120 Shirred or formed of other shape or orna- 130

mentation as may be desired, as is indicated in Fig. 7.

The stiffening means for the bag shown in Fig. 6 may be in the form of a series of fibre members 55 which may be enclosed in silk or the like and secured in stiffening position by means of snap fasteners 56^a, 56^b. The stiffening members 55 may be two in number, namely, at the top i. e., adjacent the handle 50, 51 and at the bottom, and auxiliary members 55 may be employed at the opposite sides and additional stiffening members employed and removably secured in position. The pocket 57 is shown on the inner face of the side member 42 for receiving the stiffening members 55 when not in use.

The bag shown in Fig. 8 is rectangular in outline and the material of the bag may be of patent leather or the like having the characteristics as set forth herein. The side member 60 may be secured by stitchings to the peripheral member extending at the opposite ends 61^a, 61^b and the upper and lower sides 61^c, 61^d and the opposite side member 62 partly secured to the four portions 61^a, 61^b, 61^c, 61^d, of the peripheral member and its remaining portion 62^a serving as a closure flap. The snap fasteners of the flap 62^a are indicated at 63^a, 63^b. The stiffening means is in the form 30 of the series of strips 64^c, 64^d, respectively in the inner faces of the upper and lower portions 61^c, 61^d, of the peripheral member and similar strips 64^a, 64^b, respectively in series on the inner faces of the end portions 61^a, 61^b of the peripheral member, which strips are removably held in stiffening position by means of pivot buttons or fasteners 65. To afford stiffness to the material in the direction of the length of the upper and lower portions 61^c, 61^d of the peripheral member, the same are turned at the edges as indicated at 66, or the series of stiffening strips 61^c may be connected to one another by one or more longitudinal stiffening strips 67, pivotally connected by pivot buttons 68 to the respective strips 67. Such longitudinal strips 67 serve also to swing the transverse stiffening strips 61^c, 61^d respectively from stiffening position into non-stiffening position and vice versa.

The handle of the bag shown in Fig. 7 may be in the form of a pair of loops 69, 70, the ends 69^a of the handle loop 69 being secured to the closure flap 62^a and the ends of the handle loop 70 being secured to the material of the body of the bag. The ends 69^a, 70^a of the respective handle loops 69, 70 are preferably secured in substantial alignment with two transverse stiffening strips 61^c when the latter are set in stiffening position.

Whereas patent leather and imitation leather are preferred as material of the bag proper, it will be understood that other material may be employed which is collapsible when the stiffening means is out of stiffening

position, but which material possesses sufficient body that when the stiffening means is in stiffening position the contour of the bag is preserved.

From the above, it will be perceived that the material of the container may be of non-self-sustaining character to afford ready collapsibility of the bag when desired; the stiffening means in the form of the coacting stiffening flaps or other members, which when properly positioned relative to the material of the bag imparts the feature of self-sustaining to the bag as a whole, and thereby enables hats or like articles of delicate or crushable nature to be readily carried without injury.

The invention is further advantageous in that the construction lends itself to various forms of design and ornamentation and for enclosing a large variety of articles.

It will also be noted that the handle, particularly when the stiffening members are in stiffening position, effects convenient carrying of the bag manually or about the arm of the person and ensures effective closure of the bag when suspended.

Whereas I have described my invention by reference to specific forms thereof it will be understood that many changes and modifications may be made without departing from the spirit of the invention.

I claim:

1. A container of the class described formed of substantially self-collapsible material, removable stiffening means for holding said material in self-sustaining expanded position, and means disposed inwardly of the container for removably securing said stiffening means in position.

2. A bag comprising a peripheral member and oppositely disposed side members, said peripheral member and said side members being of non-self-sustaining material, one of said side members being secured for a portion of its periphery to one edge of said peripheral member, the remainder of its periphery being unsecured to form a closure flap to provide an opening to afford access within the bag, fastener means for closing said closure flap relative to said peripheral member, the other of said side members being secured to the opposite edge of said peripheral member, stiffening sheet material secured to said peripheral member for holding said peripheral member and therewith said side members in distended position and handle means for suspending the bag, said handle means being secured to said peripheral member.

3. A bag formed of substantially self-collapsing material shaped as a container, a portion of the material serving as a closure flap, means for holding the closure flap in closed position, stiffening means for holding the material in self-sustaining expanded position,

said stiffening means being disposed inwardly of the bag and means for removably securing said stiffening means in position.

4. A bag formed of substantially self-collapsing material shaped as a container and provided with an opening, a portion of the material serving as a flap for closing the opening, stiffening means for holding the material in self-sustaining expanded position, means for removably securing said stiffening means in position and a pair of coacting members serving as a handle connected respectively to said flap and to the body portion of the bag.

5. A bag formed of substantially self-collapsing material shaped as a container, a portion of the material serving as a closure flap, means for holding the closure flap in closed position, stiffening means for holding the material in self-sustaining expanded position, said stiffening means being disposed inwardly of the bag, means for removably securing said stiffening means in position and a handle device connected at its ends respectively to said closure flap and to the body portion of the bag.

6. A bag formed of substantially self-collapsing material shaped as a container, stiffening means for holding the material in self-sustaining expanded position, said stiffening means being disposed inwardly of the bag, means for removably securing said stiffening means in position and means secured to an inner face of the material for holding said stiffening means when removed out of stiffening position.

7. A bag formed of substantially self-collapsing material shaped as a container, a portion of the material being detached to serve when closed as a closure member and when opened to provide an opening to afford access into the bag, spaced stiffening members for holding the material in self-sustaining expanded position, means for removably securing said stiffening means in position and means secured to the material for holding said stiffening members when removed out of stiffening position.

8. A bag formed of substantially self-collapsing material arranged to have a circular side, a circumferentially extending central portion and an opposite circular side, a portion of the material of said last-named circular side being detached to serve when closed as a closure flap and when opened to provide an opening to afford access into the bag and stiffening means coacting with said circumferentially extending central portion to hold said central portion and said sides in self-sustaining expanded position.

9. A bag formed of substantially self-collapsing material arranged to have a circular side, a circumferentially extending central portion and an opposite circular side, a portion of the material of said last-named cir-

cular side being detached to serve when closed as a closure flap and when opened to provide an opening to afford access into the bag and stiffening means removably secured to the inner face of said circumferentially extending central portion to hold said central portion and said sides in self-sustaining expanded position.

10. A bag formed of substantially self-collapsing material arranged to have a circular side, a circumferentially extending central portion and an opposite circular side, a portion of the material of said last-named circular side being detached to serve when closed as a closure flap and when opened to provide an opening to afford access into the bag, stiffening means coacting with said circumferentially extending central portion to hold said central portion and said sides in self-sustaining expanded position, and a handle for the bag comprising an element secured in fixed relation to said central portion and a coacting element secured to said closure flap.

11. A bag formed of substantially self-collapsing material and shaped as a container, a portion of the material being detached to serve when closed as a closure flap and when opened to provide an opening to afford access into the bag, disconnectable means for holding said flap in closed position, stiffening means disposed inwardly of the bag for holding said material in self-sustaining expanded position and means for removably holding said stiffening means in position.

12. A bag formed of substantially self-collapsing material and shaped as a container, a portion of the material being detached to serve when closed as a closure flap and when opened to provide an opening to afford access into the bag, disconnectable means for holding said flap in closed position, stiffening means disposed inwardly of the bag for holding said material in self-sustaining expanded position and means for removably holding said stiffening means in position.

13. A bag formed of substantially self-collapsing material arranged to have a circular side, a circumferentially extending central portion and an opposite circular side, a portion of the material of said last-named circular side being detached to serve when closed as a closure flap and when opened to provide an opening to afford access into the bag and spaced stiffening members disposed inwardly of the bag and coacting with said circumferentially extending central portion to hold said central portion and said sides in self-sustaining expanded position.

14. A bag formed of substantially self-collapsing material arranged to have a circular side, a circumferentially extending central portion and an opposite circular side, a portion of the material of said last-named circular side being detached to serve when closed as a closure flap and when open to provide

an opening to afford access into the bag and removable spaced stiffening members coacting with said circumferentially extending central portion to hold said central portion 5 and said sides in self-sustaining expanded position.

15. A bag formed of substantially self-collapsing material and shaped as a container and provided with an opening, a portion of 10 the material serving as a flap for closing the opening, stiffening means for holding the material in self-sustaining expanded position, means for removably securing said stiffening means in position and means for suspending 15 the bag.

16. A hat bag formed of substantially self-collapsing material and shaped as a drum and provided with an opening, a portion of 20 the material serving as a flap for closing the opening, stiffening means disposed inwardly of the bag for holding the material in a self-sustaining expanded position and means disposed inwardly of the bag for removably securing said stiffening means in position.

25 17. A hand-bag of the character described comprising a peripheral band, flexible disk sides seamed at their edges to the edges of said band, a portion of the material of one of 30 said sides forming a closure flap, and a handle comprising a strip secured at one end in the seam at one side of the bag and a tab secured to the free edge of the closure flap, and means on the free ends of said strip and tab for detachably securing them together.

35 18. A bag comprising a peripheral member and oppositely disposed side members, said peripheral member and said side members being of non-self-sustaining material, one of said side members being secured for a 40 portion of its periphery to one edge of said peripheral member, the remainder of its periphery being unsecured to form a closure flap to provide an opening to afford access within the bag, fastener means for closing 45 said closure flap relative to said peripheral member, the other of said side members being secured to the opposite edge of said peripheral members, stiffening sheet material secured to said peripheral member for holding 50 said peripheral member and therewith

said side members in distended position and handle means for suspending the bag, said handle means comprising a handle strap having one end secured to said closure flap.

19. A container comprising non-self-sustaining material serving as the material of the container proper, stiffening means for holding said material to conform to the full contour of the container and means for removably securing said stiffening means in 55 position.

20. A container comprising non-self-sustaining material serving as the material of the container proper, a plurality of stiffening means respectively at spaced locations 65 within said container, for holding said material to conform to the full contour of the container, and means for removably securing the said stiffening means in position.

21. A container comprising non-self-sustaining material serving as the material of the container proper, a plurality of stiffening means respectively at spaced locations within said container for holding said material to conform to the full contour of the 75 containers, and means disposed within the container for removably securing said stiffening means in position.

22. A container comprising non-self-sustaining materials serving as the material of 80 the container proper, stiffening means for holding said material to conform to the full contour of the container and snap fastening means for securing said stiffening means in position.

23. A hand bag of the character described comprising a peripheral band, flexible disk sides seamed at their edges to the edges of said band, a portion of the material of one of 90 said sides forming a closure flap, and a handle comprising a strap secured at its one end at one side of the bag and a second strap secured at its one end to an opposite side of the bag, and means on the free ends of said handle straps for detachably securing them 95 to one another.

In testimony whereof I have signed this specification this 24th day of November, 1922.

HELEN C. GAMBLE.
